STUDIO LOUNGE

Ulysses Bruce McMurtry, Toronto,
Ontario, CanadaApplication September 27, 1933, Serial No. 691,201
In Canada September 28, 1932

4 Claims. (Cl. 5—185)

The present invention relates to studio lounges and has for its object the provision of a device of this kind in which twin beds and double beds can be made, or the whole device formed into a 5 single structure of very compact form merely occupying the space required for a single studio lounge.

Another object of the invention is the provision of a removable bed member, which is capable 10 of being either completely placed within the limits of a single studio lounge structure or completely withdrawn and detached from same. The removable bed member just mentioned is provided with disappearing ends which may be completely 15 enclosed within the exterior walls of said member, or withdrawn and placed in a vertical position thereby forming a separate bed structure.

The removable bed member is constructed of proper proportions to permit its association with 20 a similar rigid bed structure in such fashion as will permit of both beds being level and of equal height, the one with the other.

The removable bed member is constructed so 25 that the ends of same disappear beneath it rather than on top thereof, and provides a very neat structure for the purpose intended.

Other details and advantageous features of this device will be explained as the description proceeds herein.

30 In the accompanying drawings forming part of this specification, I have illustrated two forms of the invention, which embody somewhat similar principles of invention.

35 In Figure 1 of the drawings is shown a front side elevation of the studio lounge, part of which is in section.

Figure 2 is a partial side elevation of the removable bed member with the end thereof in extended and upright position.

40 Figure 3 is a transverse vertical section on line 3—3 of Figure 2.

Figure 4 is a reverse or bottom view of Figure 2, showing the end of the removable bed member in folded position within the enclosing walls of 45 same.

Figure 5 is a partial vertical section on line 5—5 of Figure 1.

Figure 6 is an end view of the removable bed member taken from the left of Figure 2.

50 Figure 7 is an end view of the lounge shown in Figure 1, taken from the right of same.

Figure 8 is a front elevation, of a modified type of lounge or cot partially cut away to illustrate 55 the construction of same.

Figure 9 is a partial reverse, or bottom view of the removable bed member shown in Figure 8.

Figure 10 is a side view of the two bed members shown in Figure 8 when same are in collapsed position for shipping purposes.

Figure 11 is an enlarged partial transverse section on line 11—11 of Figure 8.

Figure 12 is an end view of Figure 8.

Figure 13 is an enlarged partial section taken on line 13—13 of Figure 12.

Figure 14 is a partial plan view of a removable bed member similar to that shown in Figure 2, of a modified form of the device.

Figure 15 is an end view of Figure 14 taken from the left thereof.

Figure 16 is a transverse section taken on line 16—16 of Figure 14.

Figure 17 is an enlarged side elevation of a spring catch used with the modified form of the device.

Figure 18 is a front elevation of the catch shown in Figure 17 taken from the right thereof.

Figure 19 is a partial front elevation of the type of bed member shown in Figure 14.

In the type of the device shown in Figures 1 to 7 inclusive of the drawings, the numeral 1 indicates a studio lounge which is a type of davenport and has a fixedly mounted bed member 2, secured rigidly to the two ends 3, 4 at points 5, 6 etc. The fixed member 2 is rigidly supported on 30 the angle irons 1, 8 which are in turn rigidly mounted on the ends 3 and 4 just mentioned.

Beneath the fixed bed member 2 is the removable bed member 9, which is adapted to be slid into position thereunder on the two angle-iron runways 10 and 11, as is at once understood. The rear ends of the angle-irons 10, 11 are both turned upwardly at 12 to provide stops for the removable bed member 9, as is at once understood from Figures 5 and 7.

40 The removable bed member 9 is constructed of the two stringers 13, 14, and the two end cross-pieces 15, 16, the same being made of considerable thickness and relatively strong, and have two recesses 17, 17 in each for the purpose described below. The bottom surface and ends of the cross-pieces 15, 16, are provided with a metal strip 18 in order to provide a sliding surface having a minimum of friction, and to prevent excessive wear on the cross-bars, thereby insuring ease 45 of manipulation when the member 9 is slid thereon. By extending the metal strips upwardly at 19, 19, on each end of the cross-bars, rigidity is given to the bed member 9.

Within the side stringers 13, 14, of the mem- 55

ber 9, operate the bars 20, 21 at each end of said member, which are pivotally mounted at 22, 23 respectively on the stringers 13 and 14. The opposite ends of the bars 20, 21 are also pivotally mounted at 24, 25 respectively to each movable end 26 of the removable bed member 9. It is clearly seen from Figures 1, 2 and 4 of the drawings, the end 26 can be placed either in the upright position shown in Figure 2, or can be folded 10 into the position shown in Figures 1 and 4, the bars 20 and 21 being bent to pass each other at points 27, 28 in each respectively.

It will be noted from Figures 6 and 7 of the drawings that the end 26 of the removable bed 15 member 9 is narrower in width than the end 4 of the fixed bed member 2, which is a requirement found necessary in order to fold the end 26 within the walls of the removable bed member 9, and clearly shown in Figure 4. It is seen, however, 20 that the overall width of the member 9 is equal to the overall width of the member 2, so that each of the beds are of substantially equal width and adapted to support cushions 29 and 30 which are of the same width.

25 When the end 26 of the bed member 9 is in a position shown in Figure 2, it is seen from Figure 3 that the bars 20 lie within the recesses 17, 17 of the cross-piece 15 and engage against the metal strip 18, and in this manner the bed member 9 is supported by means of bars 20, 20 on the end 26, while the bar 21 acts as a tension member to hold the end 26 in a vertical position.

Each of the bed members 2 and 9 is provided 35 with a webbing such as 31, adapted to support the cushions 29 and 30 respectively, said webbing being attached in each case across the upper surface of the bed member. The webbing in each case is preferably covered with a cloth covering 32, illustrated in Figure 4, for the sake of appearance, and it will be noted that a hand-hole 33 is provided in the webbing and its covering for a 40 purpose to be described below.

When the end 26 is in the position shown in Figure 1, it is necessary to hold the portion 34 45 in folded position. To accomplish this a cross-bar 35 is provided rigidly mounted on the front and rear stringers 13 and 14 of the member 9, and ring-bolts 36, 37, and a hook 38 provided for this purpose. The hand-hole 33 permits the 50 hook 38 to be connected or disconnected as desired, from the ring-bolt 36. While the parts which operate the end 26 have only been described with reference to one end of the member 9, it will be understood that both ends of said member 9 are provided with similar parts in substantially the same manner.

60 A central cross-bar 39 is rigidly mounted between the stringers 13, 14 and a universal swivel castor 40 is mounted thereunder, as clearly shown in Figures 1 and 4. This is a special feature of the present device which has been found to be very advantageous when manipulating the bed member 9, and inserting same on the angle-irons 10 and 11 for the reason that the said member 65 can be balanced on said castor, and easily moved to permit a ready entrance on said angle-irons. By "balancing" member 9 on the universal castor 40 is meant that as the castor is placed at the centre of gravity of the member 9 the weight of the 70 latter centers on the castor, and this being the case the whole member 9 can be easily manipulated into a truly horizontal and perfectly level position, which is readily seen to be an absolute necessity, as is found through practical use, before the frame can be slid inwardly on the angle

75 irons 10, 11 of the bed-ends 3, 4. Moreover, the castor 40 prevents the member 9 when the ends 26 are in a folded position, from lying flat on the floor when the said member is withdrawn, so that the fingers may be readily inserted beneath the member to manipulate it while the castor holds said member at the right elevation to be inserted 80 between the ends 3, 4 and the angle-irons 10 and 11. It will be noted that the "right elevation" means that by making the central castor of sufficient height, so that the bottom end edges of the lower bed hardly touch the upper surfaces of the guides 10, 11 and by slightly balancing the bed member on the central castor, there is a very easy sliding action along the guides. This 85 is due to the fact that the weight of the bed member is practically all on the central castor (same being its gravitational center), and not on the surface of the guide angles 10, 11.

The operation of the device just described is 90 readily understood, but will be briefly described as follows. When the member 9 is in position shown in Figure 1, and the cushions 29 and 30 superimposed upon each other, a single structure is provided thereby, forming a studio lounge. When 95 it is desired to form twin beds or a double bed, the removable bed member 9 is withdrawn from the structure, the hooks 38, 38 are each disengaged in turn from the ends 26, 26 and by lifting each end of the member 9 in turn, the ends 26, 26 fall downward as shown in the dotted position 41 of Figure 2, from which position they are lifted 100 by the hand to vertical position shown in said figure.

It is found when extending the end 26 from the 105 member 9 that same can be best accomplished by holding fast to the webbing 31 at point 42, Figure 4, at the edge of the hand-hole 33. When both ends 26 are extended in vertical position, the top cushion 30 may be placed on the removable 110 bed member 9, and the top surfaces of the cushions 29, 30 are of equal height from the floor, and a double bed thereby provided. The cushions 29 and 30 on their bottom sides are made to resemble mattresses, and on their top surfaces, are of 115 cloth of various designs. Loose cushions (not shown) of small size may also be provided and placed against the wall of a room when the device is used as a studio lounge.

120 It will be seen that the removable member 9 is entirely separate from the fixed bed member 2 and its ends 3, and 4, and really two beds are provided, which may be placed in separate rooms of a house when necessary.

The structure shown in Figures 8 to 13 of the 125 drawings may be described as follows. An upper bed member 50 is provided having the ends 44, 45 which are pivotally mounted by means of the bars 46, 47 on the front and rear stringers 43, 48. The operation of the members 46 and 47 is substantially the same as the members 20 and 21 of the first described type of the device. However, 130 angle-irons are used for the parts 43, 48, 44, 45 in this cot structure. The cross-pieces 48a are also constructed of angle-irons, as seen from Figure 8, the end 44 folds within the stringers 43 and 48, as in the case of the end 26, in the first form of the device.

The lower bed member 49 is substantially like 135 the upper bed member 50, and has practically 70 similar structural parts except that the castor 51 is placed in this instance on the rear angle-iron 52 of said member. Instead of the webbing as in the case of the first form of the device, springs 53 are used in this cot structure to support the 75

cushions 54 and 55. The cushion 54 is provided with depending draperies 56, as shown in Figure 8 clearly.

The end 44 is provided with cross-members 57 made of angle-irons and attached to the uprights 58, 58 as shown in Figures 12 and 13. A transverse guide-angle 59 is mounted on the cross-bar 51 to form a guide for the cross-pieces 60, of the lower bed member 49. It is seen from Figure 10 that both members 49 and 50 can be placed one on top of the other as shown in Figure 10 for shipping purposes. Figure 11 shows the arrangement of the bars 46 and 47 and associated parts in this type of the invention.

It will be noted that in the metal cot form of the device, both the upper and lower bed members are collapsible, whereas in the structure first described, only the removable bed member 9 is so. A thin metal strap 61 preferably yieldingly mounted at 62 on the uprights 58, 58 of the ends 44 and 45 is provided to prevent small cushions from falling through the ends of the cot, as is at once understood.

The operation of the cot device, it is believed, is obvious from what has been said above, and will not be further described.

The structure shown in Figures 14 to 19 inclusive of the drawings is a modified form of a removable bed member to be used in lieu of the type shown in Figures 1, 2 and 3 above described, and may be described as follows:

The frame of the bed member comprises two angle-iron stringers 63, 64 which are rigidly connected by two angle-iron opposed cross members 35 similar to 65. The bed end 66 in this form of the device is mounted in the same manner as shown in Figure 2, the bars 67 and 68 being mounted at their inner ends in the angle-irons 63, 64 and at their outer ends on a plate 69 which is in turn 40 mounted on the upright 70 of the bed end 66. It is found that by using a plate 69, the end of the bars 67, 68 may be mounted in a more smoothly operating manner on the bed ends. When the bed end 66 is swung into position as shown in 45 Figure 14 within the stringers 63, 64 a spring catch 71, which is shown clearly in Figures 16 to 18 inclusive, is used to hold the bed end in secure position, and it will be noted that in swinging the bed end into said position, the part 72 first 50 engages the stringers 63 or 64 as the case may be and due to the yielding nature of the spring 73, the part 72 is pushed readily inward toward the centre line of the bed and climbs into a locked position on the stringers as shown in Figure 17.

It is seen that when the bed end 66 is in retracted position as in Figs. 14 and 16 the bed end is supported by the spring catches 71, 71 which are secured to the horizontal flanges of the longitudinal stringers 63, 64; these catches act as a 55 fulcrum point so far as the bed end 66 is concerned, and as the portion to the right of the fulcrum as seen in Fig. 14 is comparatively short and the opposite end of the bed end is comparatively long, there is a tendency for the long or 60 left end 74 to drop downward below the bottom edges of the stringers 63, 64.

In order to keep the portion 74 of the bed end 66 from protruding beneath the bottom of the stringers 63, 64 a pair of gutta percha bumpers 75, 75 (Fig. 14) are mounted in the inner side of the bottom of the bed end 66 and engage against the underside of the horizontal flanges of said stringers and prevent the end 74 of the bed end from hanging down lower than the bottom edge of the 70 stringers 63, 64 as it is at once understood. In order

to more easily pull the bed end 66 into retracted position as shown in Figure 14 a handle 76 is provided on said bed ends, about in line with the two spring catches 71, 71. Another handle 77 is mounted on the cross-piece 65 in order to more 6 easily manipulate the bed ends 66 when they are swung into horizontal or vertical position, as is at once understood. On the vertical flange of the cross-piece 65 are mounted two rollers 78, 78 as clearly shown in Figure 15.

The removable bed member 79 may be used with the type of structure shown in Figure 1 and due to having rollers 78, 78 on each end of the removable bed member, the guideways 10 and 11 become unnecessary and said lower bed member 15 can be slid into position beneath the upper bed member.

It will be noted from Figures 15 and 19 that, as in the case of the structure shown in Figures 2 and 3, the end of the cross member 65 is slotted 20 at 80, 80 to receive the bars 67, 68. However, in the modification, due to the use of the spring catches 71, additional slots 81, 81 become necessary in the cross member 65 to accommodate the spring catches 71, 71 when the bed is in the position shown in Figure 19: also in Figures 14 and 19 it will be noted that at the bottom ends of the bed member 79 there are two sliding shoes 82, 83 mounted on the lower corner of the bed end. These shoes are merely polished buttons with 30 prongs therein which are pressed into the corner of the bed end 66, so that when same is being slid along the floor from its upright position to its retracted position within the the stringers 63, 64, it will operate smoothly along the floor.

It will be observed that in lieu of these sliding shoes 82, 83 small castors of the ordinary type may be substituted (not shown), if same are found more convenient for the purpose.

It will be noted, in this form of the device, that 40 the lower bed member 79 may be arranged comparatively close to the floor in order to give space between the two bed members for the storage of bed clothes and in this case it is found desirable to add a front board 84 which is attached by 45 means of the angle-irons 85, 86 etc., to the horizontal flange of the front stringer 64 in order to prevent the said bed clothing being seen from the front of the studio lounge.

The operation of this modified form just described is as follows:

As has been suggested above in the specification, this type of removable bed member may be used with the type of fixed upper bed member similar to that shown in Figure 1, except that the guideways 10 and 11 and the central castor 40 are unnecessary; and when used with the type of cot shown in Figure 8 the transverse guide-angles 59, 59 and the central castor 51 are also unnecessary,—since the removable bed member 79 is provided with the castors 78, 78 on both ends thereof, and is merely pushed into position beneath the upper bed member, as is readily understood.

In folding the bed ends 66, 66 from a perpendicular to a retracted position, the handle 77 is used 65 to support the frame of the bed member, while the bed ends are slid into retracted position. The frame is then lowered to the floor and rests on the castors 78, 78 and by means of the handle 76 the inner ends of the bed ends 66 are lifted upward until the spring catches 71, 71 engage on the top surface of the stringers 63, 64 respectively as clearly illustrated in Figure 17 of the drawings. The gutta percha bumpers 75, 75 are placed by this action close against the underside 75

of the horizontal flanges of the stringers 63, 64 so that the outer end 74 of the bed end 66 is held off the floor as before explained and as is readily understood.

5 I claim:

1. In a studio lounge, a foldable bed member, comprising a pair of stringers, and a pair of cross-pieces forming a frame, a covering of yieldable material having a pair of hand-holes there-through, a pair of movable bed ends forming supports, a double pair of movable bars for each bed end, each bar of which is pivotally connected to a stringer and a bed end, and providing a pivotally operating means adapted to swing each bed 10 end into folded position beneath the yieldable covering, and within the space enclosed by the said frame, a pair of oppositely disposed cross-bars mounted in the frame, each adjacent to and below one of the hand-holes, and fastening means 15 engaging the cross-bars in a position readily accessible through the hand holes for the purpose of detachably securing each bed end in folded position.

2. In a studio lounge having an upper bed 20 member, and a pair of bed ends therefor, a transverse angle-iron on each bed end forming a runway, a detachable lower bed member slidably mounted on said runway, an upturned end on each angle-iron at the rear side of the lounge 25 forming a stop for the detachable bed member, a second pair of bed ends pivotally mounted beneath and within the detachable bed member, adapted to be withdrawn from, and form supports 30

for same, and a swivel castor mounted beneath and at the central point of the detachable bed member, to provide a means for easy manipulation thereof when being mounted on said runway.

3. In a studio lounge, a foldable bed member, 5 having a frame, a pair of bed ends pivotally mounted on and beneath the frame, each of which is adapted to be withdrawn into an extended upright position adjacent to the ends of the frame, providing a pair of supports for said frame, locking means for holding them in position when the bed ends are retracted within the frame, and a pair of opposed bumpers near the bottom ends of each bed end, each in engagement with the frame of the bed members, for 10 preventing the upper end of the bed ends from protruding beneath the bottom of the frame, when the bed ends are in retracted position.

4. In a studio lounge, a foldable bed member, 15 having a frame, a pair of bed ends pivotally mounted on and beneath the frame, each of which is adapted to be withdrawn into an extended upright position, adjacent to the ends of the frame, providing a pair of supports for said frame, a pair 20 of oppositely mounted spring catches on each bed end, adapted to engage the edges of the frame and positively hold the bed ends in retracted position, and a pair of opposed bumpers on each bed end in engagement with the frame for preventing the bed ends from protruding beneath 25 the bottom of the same.

ULYSSES BRUCE McMURTRY.
